(57) **CLAIM**

The ornamental design for a water filter pitcher as shown and described.

DESCRIPTION

FIG. 1 is a top, front, right side perspective view of a water filter pitcher, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom, left side perspective side perspective view; and,

FIG. 9 is a partial cross-sectional view taken along line 9-9 of FIG. 6.

The dashed broken lines in the drawing depict portions of the water filter pitcher that form no part of the claimed design.
